ATTORNEY

UNITED STATES PATENT OFFICE

JOSEPH RITLEY, OF CLEVELAND, OHIO

COMBINATION POKER AND CLINKER TONGS

Application filed May 9, 1932. Serial No. 610,158.

My invention relates to a device adapted for use in connection with open grates and furnaces.

One object is to provide a means for removing clinkers from a furnace or grate with a minimum of effort.

Another object is to provide a separate unit which may be used in conjunction with an ordinary poker to complete a suitable 10 clinker tongs.

Other objects will be noted in the following specification and its accompanying drawing, and in which:

Figure 1 is a view of the ordinary poker 15 and auxiliary rod linked together; Fig. 2 is a perspective view of Fig. 1; Fig. 3 is an end view of Fig. 1; Fig. 4 is an end view showing the tongs gripping a clinker.

Referring specifically to the drawing, a 20 poker 10 of any construction similar to that shown in the drawing, is thrust thru the circular loop 11 near one end of the auxiliary rod 12, said loop ending in a right angle prong 13 with a curved end 14, the other end 25 of said auxiliary rod ending in a handle 15, at right angles to the prong 13.

The handle 15a on the poker 10 being parallel with the bent end 17 permits easy manipulation. Auxiliary rod 12 is approximately one-third shorter than the poker 10 30 to allow a free movement in manipulating the poker 10 and auxiliary rod 12 to grip a clinker 16 between the bent end 17 and the bill 14.

35 The poker 10 either swivels or moves longitudinally within the loop 11 as the clinker 16 is drawn within the scope of the tongs formed by the right angle prong 13 of the auxiliary rod 12 and the bent end 17 of the poker 10.

Said poker may be withdrawn from the 40 loop 11 and used in the ordinary manner when desired. The auxiliary rod 12 being a supplementary device may be manufactured 45 and sold as such if desired.

I claim:

The combination with a poker having a 50 bent end, of an attachment comprising a rod bent laterally to form a loop through which the poker extends, the end of the rod beyond

the loop being bent laterally to form a prong arranged to cooperate with the bent end of the poker to form a tongs, the poker being rotatable in the loop to open and close the tongs by a pivotal movement.

In testimony whereof, I do affix my signature.

JOSEPH RITLEY.
